(57) **CLAIM**

The ornamental design for an enteral syringe, substantially
as shown and described.

DESCRIPTION

FIG. 1 is a top-front isometric view of an enteral syringe;
FIG. 2 is a front view of the enteral syringe of FIG. 1;
FIG. 3 is a rear view of the enteral syringe of FIG. 1;
FIG. 4 is a left side view of the enteral syringe of FIG. 1;
FIG. 5 is right side view of the enteral syringe of FIG. 1;
FIG. 6 is a top view of the enteral syringe of FIG. 1; and,
FIG. 7 is a bottom view of the enteral syringe of FIG. 1.
The syringe is shown with a symbolic break in its length.
The appearance of any portion of the article between the
break lines forms no part of the claimed design.
The broken line showing of parts of the drawings is included
for the purpose of illustrating use and environment and
forms no part of the claimed design.

1 Claim, 4 Drawing Sheets
